UNITED STATES PATENT OFFICE.

SIMON LAKE, OF MILFORD, CONNECTICUT.

SUBMARINE BOAT.

Specification of Letters Patent.

Patented Feb. 1, 1916.

1,169,970.

Application filed August 16, 1915. Serial No. 45,695.

To all whom it may concern:

Be it known that I, SIMON LAKE, a citizen of the United States, residing at Milford, in the county of New Haven and State of Connecticut, have invented certain new and useful Improvements in Submarine Boats, of which the following is a specification.

The invention relates particularly to an improved submarine or submersible boat designed for commercial purposes, and particularly for carrying cargoes of various description.

The invention consists in the peculiar and novel construction of a non-pressure-resisting outer hull; of the arrangement of a pressure-resisting inner hull in which is arranged an engine compartment, a working compartment, and living quarters; in the peculiar and novel arrangement of tanks within the outer hull which are designed for carrying the cargo; and in the novel manner of bracing said tanks in position and to the outer hull, the whole being so arranged as to provide a thoroughly rigid construction of relatively light weight material.

The invention further consists in certain novel features of construction and peculiar combinations and arrangements of parts as will hereinafter be fully described and then claimed.

In the drawings, illustrating the invention, in the several figures of which like parts are similarly designated, Figure 1 is a diagrammatic vertical longitudinal section of my improved cargo-carrying submarine or submersible boat. Fig. 2 is a transverse section of the same drawn on a slightly larger scale on the line *a—a* of Fig. 1. Fig. 3 is a horizontal section of the same drawn through the forward end of the boat on the line *b—b* of Fig. 1, the cargo-carrying tanks being shown in plan. Fig. 4 is a detail vertical sectional view on a larger scale drawn through the lower end of one of the tanks, illustrating the manner of connecting the tanks to their supporting plates and to their horizontal partitions.

1 designates the outer hull of the boat of any desired cross-sectional form, but in preference, non-circular so as to provide

lines best suited for surface navigation, the hull being constructed of relatively light weight plating 2 and ribs 3 (Fig. 2), and, as will hereinafter appear, is not designed as a pressure-resisting body. The space within the hull is divided by transverse partitions 4, 5 and 6, which are connected to the ribs 3 of the hull 1 in the usual manner. In practice, the partitions 4 and 5 will be of sufficiently heavy weight material to resist the pressure incident to submergence, and within the space formed by the said partitions, there is arranged an inner pressure-resisting hull 7, preferably substantially cylindrical in cross-section, and constructed of plating 7' and ribs 7'' (Fig. 2), as is usual in single hull submarine boats. The respective ends of the inner hull 7 are connected air- and water-tight to the bulkheads 4 and 5, and in practice, the inner hull is divided by transverse partitions 8 to provide an engine and machinery compartment 10, an operating compartment 11, and a living compartment 12. Doorways 75 are provided in the partitions 8, and are controlled by doors 9 preferably opening into the working compartment.

13 designates a superstructure built upon the top of the outer hull 1. By preference, the superstructure is provided with inlet valves (not shown) so that the space formed by the superstructure may be flooded when the boat is submerged, but as this feature forms no part of the present invention, it is not thought necessary to illustrate or to describe the same in detail. Upon the deck of the superstructure is built a coaming 14, preferably glass, substantially as shown in my co-pending application, Serial No. 9017,797, filed March 29, 1915. Access to the working compartment 11 of the inner pressure-resisting hull is had through a hatchway 15, having its upper end connected to the under side of the deck of the superstructure 13, and its lower end connected air- and water-tight to the top of the inner pressure-resisting hull 7, hatchways being provided in the deck of the superstructure and in the top of the inner pressure-resisting hull 7, said hatchways being controlled by outwardly opening doors or covers 16.

so as to prevent inlet of water to the hatchway and to the inner hull when the boat is operating submerged, or when operating in rough weather when seas are liable to break 5 over the coaming 14.

17 designates a sighting instrument preferably slidably mounted in the boat and having its lower end extended into the operating compartment of the inner hull 7, 10 whereby observations may be made when the boat is operating entirely submerged, and with the coaming 14 slightly below the surface of the water.

The space within the outer non-pressure-resisting hull between the partitions 4 and 5 and the inner pressure-resisting hull 7, is divided by a horizontal partition 18 (Fig. 2), and connected air- and water-tight to the lower side of this partition is a substantially U-shape trough 19 having closed ends 20. The upper longitudinal edges of the sides of the trough 19 and its ends 20 are connected air- and water-tight to the horizontal partition 18, whereby to provide 25 a battery compartment 19' in which is arranged the battery cells 21 from which the necessary power is derived for operating the boat submerged and when in submerging condition. Access to the battery compartment 19' is had through a hatchway controlled by a cover 19'', as shown in Fig. 1.

As shown, the battery compartment does not extend throughout the length of the space formed between the transverse partitions 4 and 5, so that a well 22 is provided at each end of the battery compartment. Mounted in each well is a hydraulic cylinder 23, in each of which operates a piston (not shown), the rod 24 of each having its 40 lower end connected to one end of an arm or lever 25, pivoted intermediate its ends to the sides of a recess formed in the keel 1' of the outer hull 1, and the free end of each is provided with journals in which are 45 mounted a bearing roller or traction wheel 26, the wheels being designed to contact with the water-bed when the boat is operating upon or immediately adjacent to the water-bed. As the construction and the operation 50 of these traction wheels forms the subject matter of Letters Patent No. 726,705, granted to me April 28, 1903, it is not thought necessary to describe the same in detail, and attention is therefore invited 55 to the said patent for further understanding of their purpose.

The spaces formed between the outer non-pressure-resisting hull; the transverse partitions 4 and 5, and the inner pressure-resisting hull 7, also the spaces in the forward end of the boat formed by the transverse partitions 5 and 6, and also the space in the after end of the boat, aft of the transverse partition 4, are divided by horizontal par-

titions 18' having openings formed therein controlled by valves 182 (Fig. 2), the stems of the valves being extended into the inner pressure-resisting hull 7, whereby the valves may be operated from within the several compartments of the said hull section 7, as 70 will be hereinafter described.

The spaces upon the opposite sides of the inner pressure-resisting hull 7, between the partitions 18 and 18', are divided by horizontal partitions 18'' having their inner and outer longitudinal edges connected, respectively, with the plating of the inner hull 7 and the plating of the outer hull 1, and their forward and after edges connected, respectively, with the transverse partitions 80 4 and 5, said horizontal partitions 18'' having a plurality of openings (not shown) whereby the spaces above and below the latter partitions are in open communication. The spaces in the forward end of the boat, 85 formed by the partitions 5 and 6, are divided by horizontal partitions 181, the spaces thus formed being also in open communication through openings 183, shown in Fig. 3.

The partitions 18, 18', 181, and 18'' are formed with circular openings 27 (Fig. 4) through which extend vertically arranged cargo-carrying tanks 28. The lower ends of the tanks are mounted upon transverse 90 horizontal plates 29, arranged preferably in step-like order so as to meet the conditions imposed by the longitudinal and transverse curvature of the outer hull 1. Suitable longitudinal girders 30 are provided to 100 strengthen the horizontal plates 29 and the bottom of the U-shape trough 19, and, in practice, it will be understood that the girders and the plates will be securely connected together and to the plating of the 105 ribs of the outer hull 1 as in all ship constructions.

In practice, the tanks are provided at their lower ends with flanged rings or frames 26' (Fig. 4), which are securely 110 riveted to their supporting plates 29, and are also connected to their respective horizontal partitions by means of circular rings or frames 31, shown most clearly in Fig. 4, said rings or frames being L-shape in 115 cross section, and riveted to the tanks and to the said horizontal partitions. The tanks 28 are provided in their tops with openings controlled by suitable covers 32, and the deck 1'' of the outer hull is formed with 120 alining hatchways controlled by suitable covers 33, so that access to the tanks may be readily had from the deck of the boat when loading or removing the contents into and from the said tanks.

In practice, the upper partitions 18' will be connected air- and water-tight at their longitudinal edges to the sides of the outer

hull 1, so as to provide water-tight compartments in the upper portion of the outer hull to thus add buoyancy to the boat when operating upon the surface. When the boat 5 is submerged, the valves 182 (Fig. 2) will be opened so as to permit water to flow into the spaces above the partitions 18', as well as into the superstructure, through the valves heretofore referred to, so as to prevent 10 the collapse of the deck of the boat, it being understood, of course, that when the boat is submerged, the sea-valves (not shown) controlling the admission of water-ballast to the lower compartments of the 15 boat will be opened so that the water may flow into and through the several compartments of the outer hull, and into the spaces formed above the horizontal partitions 18'. To empty the various water-ballast compartments, I purpose connecting them with 20 pipes (not shown) extending from suitable compressed air-storage bottles 37, preferably carried in the lower hold of the boat, that is to say, in the spaces formed below 25 the plates 29 at each side of the battery compartment 19', so that when air is admitted to the spaces, the water will be blown therefrom, it being understood, that as the water is ejected, the spaces will be replaced 30 by air of such pressure as to equalize the external pressure, and thus prevent the decks and partitions, and the sides of the outer hull from collapsing. It will be further understood, that when empty of water, 35 the spaces above the decks 18', as well as the space formed by the superstructure, will greatly add to the surface buoyancy of the boat, and furthermore, that the said spaces may be utilized as living quarters for the 40 crew when the boat is operating on the surface.

In the construction shown and described, the spaces formed between the outer non-pressure-resisting hull 1, and the inner pressure-resisting hull 7, and the spaces formed 45 at the forward and after ends of the boat are designed to be filled with water from the surrounding body of water when the boat is to be submerged, and it will, of course, be understood that suitable sea-valves (not 50 shown), operated preferably from within the several compartments of the inner pressure-resisting hull 7, will be provided for controlling the admission of water to the 55 aforesaid spaces. Suitable pumps (not shown) will also be provided for pumping the water from the said spaces to emerge the boat.

The tanks 28 are constructed of sufficiently heavy weight material to withstand the pressure of submergence equal to that for which the inner pressure-resisting hull 7 is designed, and when empty, or when carrying such materials in which air spaces

are left in the tanks, that is to say, materials other than liquid, or when the tanks are not completely filled with liquid, I purpose admitting air under pressure to the tanks so as to prevent any possibility of collapse, the air being led into the tanks 65 through pipes 36 (Figs. 1 and 2), extending from a suitable source of supply (not shown), the supply source being furnished with air either by a suitable air pump (not shown), similar to those installed upon all 70 submarine boats, or from the compressed air bottles 37 carried in the lower part (or hold) of the outer hull upon either side of the battery compartment 19', as hereinbefore described. 75

It will be understood that in the construction shown, the entire space between the outer and inner hull sections forms the ballast compartment or tank of the boat, and that when the boat is submerged, the cargo-carrying tanks will be entirely surrounded by water, so that I am able to build a strong and durable outer hull, as well as the superstructure, of comparatively light weight material and, of sufficient strength to avoid 80 danger of collapse when operating upon the surface in rough weather. It will be further understood that I may provide the several cargo-carrying tanks with sea-inlet valves, whereby water-ballast may be admitted into any of the tanks in order to trim 85 the boat when full loads are not carried within the tanks. 90

By my construction, I provide a boat with a larger amount of reserve buoyancy, and 100 consequent greater surface buoyancy than has heretofore been produced. It will be further understood that the tanks may be connected together and to the outer hull, and to their adjacent partitions by suitable 105 braces, but as these latter features constitute details of construction well known by those skilled in naval architecture, it is not thought necessary to show or to describe them. 110

It will thus be seen that I provide an exceedingly novel construction of submarine or submersible boats particularly designed for carrying cargoes of various descriptions, and which will be found of inestimable advantage in supplying blockaded countries with food-stuffs or war materials during hostilities, and which may be readily submerged, when upon the high seas, in the event of interception by an enemy's fleet. 115 When operating in danger zones, such for instance, as in the presence of hostile ships, and when entering a blockaded port, the crew of the submarine will enter the inner pressure-resisting hull section and from the 120 said section navigate the boat past the hostile ships, it, of course, being understood that the boat will, from time to time, be 125

navigated to permit the sighting instruments of the boat being projected above the surface to enable the occupants to obtain their bearings as in the operation of all submarine boats.

While I have briefly described the elements best adapted to the construction set forth, it is obvious that various minor changes in details of the boat, and in the 10 construction shown, may be resorted to without departing from the spirit of, or sacrificing any of the principles of the invention. Also, that my improved freight carrying boat may be provided with fenders such as 15 is shown and described in Letters Patent No. 1,135,537, granted to me April 13, 1915, assigned to the Lake Torpedo Boat Company of Maine, to thus enable the boat to be maneuvered through a mined field or under nets extended across a channel without 20 fear of detection, when entering a port.

What I claim is:—

1. A cargo-carrying submarine or submersible boat, comprising an outer hull and an 25 inner hull, cargo-carrying tanks arranged in the spaces formed by said outer and inner hulls, the spaces formed by said inner and outer hulls around said cargo-carrying tanks providing water-ballast compartments.

2. A cargo-carrying submarine or submersible boat, comprising an outer non-pressure-resisting hull section and an inner pressure-resisting hull section, said inner hull section providing machinery, working and living 35 compartments, cargo-carrying tanks arranged in the spaces formed by and between said inner and outer hull sections, said spaces also providing water-ballast compartments.

3. A cargo-carrying submarine or submersible boat, comprising an outer non-pressure-resisting hull section and an inner pressure-resisting hull section, and a plurality of pressure-resisting cargo-carrying tanks arranged in the space formed between said outer and inner hull sections, the spaces formed around said inner hull section around said tanks also providing water-ballast compartments.

4. A cargo-carrying submarine or submersible boat, comprising an outer hull section 50 and an inner hull section, transverse and horizontal partitions arranged in the spaces formed by and between said hull sections providing a plurality of communicating compartments, and cargo-carrying tanks arranged in said spaces and extending through and connected to said horizontal partitions, the spaces formed by said partitions providing communicating water-ballast compartments.

5. A cargo-carrying submarine or submersible boat, comprising an outer non-pressure-resisting hull section and an inner pressure-resisting hull section, said inner hull section having partitions providing a plurality of

compartments as specified, transverse partitions arranged in said outer hull section and forming the ends of said inner hull section, said partitions having openings providing communications between the forward and after ends of said outer hull section at the 65 sides of said inner hull section, horizontal partitions within said outer hull having openings arranged therein, and cargo-carrying tanks extending through the openings of said horizontal partitions and braced thereto 70 as specified, the communicating spaces formed by said transverse and horizontal partitions providing water-ballast compartments. 75

6. A cargo-carrying submarine or submersible boat, comprising an outer non-pressure-resisting hull section and an inner pressure-resisting hull section, said inner hull section having partitions providing a plurality of compartments as specified, transverse partitions arranged in said outer hull section forming the ends of said inner hull section, horizontal partitions arranged within said outer hull section providing a plurality of communicating compartments, said horizontal partitions having openings therein, cargo-carrying tanks held within said openings, and flanged rings connecting said tanks with said horizontal partitions, the communicating spaces formed by the said transverse and horizontal partitions providing 90 communicating water-ballast compartments. 95

7. A cargo-carrying submarine or submersible boat, comprising an outer non-pressure-resisting hull section, and an inner pressure-resisting hull section, said inner hull section having transverse partitions providing a plurality of compartments as and for the purpose specified, transverse partitions arranged in said outer hull section, horizontal partitions arranged within the space formed by said outer and inner hull sections and in the forward and after ends of the outer hull section, said horizontal partitions having vertically aligned openings, cargo-carrying tanks mounted within said openings and braced to said partitions, said tanks having openings in their upper ends, covers for closing the openings, cover-controlled hatches formed in the deck of said outer hull and aligning with said tank openings, and means for admitting air under pressure to said cargo-carrying tanks. 100 105 110 115

8. A cargo-carrying submarine or submersible boat, comprising an outer non-pressure-resisting hull section and an inner pressure-resisting hull section, said inner hull section having transverse partitions providing a plurality of compartments, transverse partitions arranged in said outer hull section providing closures for the ends of said inner hull section, a transverse partition arranged in the forward end of the outer hull section. 120 125

horizontal partitions arranged in said outer section and connected to said transverse partition and to said hull sections as specified, and having vertically alined openings, 5 cargo-carrying tanks mounted in said openings and connected to said horizontal partitions, the space thus formed between said hull sections and the spaces in the forward and after ends of the outer hull providing communicating water-ballast compartments. 10

In testimony whereof I have hereunto set my hand this 2nd day of August, A. D. 1915.

SIMON LAKE.
